UNITED STATES PATENT OFFICE

157,756

ALBUM

Charles R. Hagen, Los Angeles, Calif.

Application September 20, 1947, Serial No. 141,516

Term of patent 3½ years

(Cl. D6—2)

To all whom it may concern:

Be it known that I, Charles R. Hagen, a citizen of the United States, residing at Los Angeles, in the county of Los Angeles and State of California, have invented a new, original, and ornamental Design for an Album, of which the following is a specification, reference being had to the accompanying drawing, forming part thereof, and wherein

Fig. 1 is a front elevational view of an album showing my new design; Figs. 2 and 3 are, respectively, opposite side edge elevations of the same; and Figs. 4 and 5 are respectively opposite end edge elevations of the same.

The initial "B" is merely representative. The front and back of the album are composed of transparent plastic material having their surfaces and edges sand-blasted except where otherwise ornamented. The back of the album is unornamented except where sand-blasted.

I claim:

The ornamental design for an album, as shown and described.

CHARLES R. HAGEN.
